FUEL BURNING APPARATUS

Otto Lotz, Oberhausen, Germany, assignor to The Babcock & Wilcox Company, New York, N. Y., a corporation of New Jersey

Original application May 31, 1952, Serial No. 290,876.
Divided and this application March 29, 1956, Serial No. 574,725

20 Claims. (Cl. 122—235)

The present invention relates to fuel burning apparatus in which the primary combustion space is suitably provided by a cyclone furnace or furnaces generally of the type disclosed in U. S. Patent No. 2,357,301. The apparatus is thus especially adapted for burning ash containing solid fuels in a relatively coarsely pulverized or granular condition, with combustion being effected at furnace chamber temperatures above the ash fusion temperature whereby there is maintained a discharge of incombustible ash residue from each cyclone furnace as liquid slag. The cyclone furnaces are suitably formed about horizontally extending axes and furthermore are arranged to discharge into a secondary furnace chamber in a generally horizontal direction, thereby constituting the source of heat for an associated fluid heating unit.

The instant application is a division of my copending application for Fuel Burning Apparatus, Serial No. 290,876, filed May 31, 1952.

The granular fuels normally used in such cyclone furnaces have particle sizes of $\frac{3}{8}$ " and under, and contain as a result of the fuel crushing operation a proportion of dustlike particles, known as "fines." The fuel and air mixture is introduced in the furnace chamber through a tangential inlet arranged to effect a whirling motion of the fuel and air mixture in a helical path axially of and toward the opposite end of the furnace. In operation the entering fuel and air stream is rapidly ignited and the centrifugal effect of the whirling stream causes the ash particles released from the burning fuel particles to deposit in a molten condition on the furnace wall and form a film or layer of molten slag thereon on which the larger fuel particles are caught and burned.

In prior embodiments of horizontally arranged cyclone furnaces, the gases of combustion are caused to enter a lower part of the secondary furnace chamber at one side of a steeply inclined dividing or intermediate wall or arch by which the gases are deflected downwardly toward the floor of the secondary furnace chamber, the flow of gases continuing in an upward direction at the downstream side of the arch and thence into a radiation chamber where the heat of the gases is transferred to fluid conducting elements disposed at elevations beyond the arch. Due to the bilateral heating, this intermediate wall is subject to a high degree of wear which is difficult to detect by observation. It also obstructs all free observation of the openings through which the furnace gases and the slag pass from the cyclone furnace chamber into the secondary furnace chamber.

In the normal operation of a cyclone furnace of the character described, there is effected within the furnace a high degree of separation of suspended slag particles from the gases in order to permit gases relatively free from slag particles to be discharged through the central gas outlet while the collected slag is separately discharged through a separate, lower outlet. Owing to this, the slag outlet is heated only by a partial gas current which is further decreased as the slag level rises thereby presenting some difficulty in maintaining slag fluidity at the

2

slag outlet. It has also been customary to position the cyclone furnace laterally adjacent and opening to the secondary furnace chamber, with the major axis of the cyclone furnace arranged substantially horizontal and the entire axial length of the cyclone furnace disposed outside the secondary furnace chamber. While satisfactory operation has been obtained with the cyclone furnace so arranged, some difficulty has been encountered in providing for effective fluid circulation in the tubes defining the cyclone furnace walls.

The present invention is concerned with the provision of an improved construction of a fluid heating unit comprising upwardly extending walls including fluid cooled tubes defining a secondary furnace chamber receiving the products of combustion directly from a cyclone type furnace, the axis of which is preferably arranged substantially horizontal and the axial length of which is disposed within the secondary furnace chamber, with some of the fluid cooled tubes of the secondary furnace chamber walls having intermediate portions forming the furnace chamber of the cyclone furnace. An outlet is arranged tangentially of the circumferential wall of the cyclone furnace for the discharge of both molten slag and high velocity gases including slag particles in suspension. The outer vertical wall of the lower portion of the secondary furnace chamber is positioned opposite the cyclone furnace gas and slag outlet at a distance sufficient to insure that the gases and suspended slag particles discharging from the gas and slag outlet will impact on the outer wall at a velocity sufficient to cause most of the suspended slag particles in a molten or sticky condition to adhere to the outer wall and thence flow downwardly to a slag pit. With this arrangement continuous discharge of slag in a molten condition through the cyclone furnace gas and slag outlet is assured. Further, the wall tubes forming the combustion chamber of the cyclone furnace are exposed to the heat of the gases on one side along a substantial portion of their length, while a portion of said tubes are subject to the heat of the gases on both sides, thus promoting continuous and effective circulation in these wall tubes. Moreover, a self-cleaning slag deposition area is provided by the outer wall of the secondary furnace chamber for effectively removing the slag particles carried out of the cyclone furnace in suspension in the heating gases discharged, and the outer wall is less exposed to wear than the intermediate gas directing arch or baffle wall heretofore employed because of the unilateral heating by gases flowing therover.

50 The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a specific embodiment of my invention.

Of the drawings:

Fig. 1 is a vertical sectional view of a cyclone furnace fired fluid heating unit constructed in accordance with my invention;

Fig. 2 is a partial vertical section taken along the line 2—2 of Fig. 1; and

Fig. 3 is a diagrammatic vertical section of a modified form of the cyclone furnace shown in Figs. 1 and 2.

While various kinds of liquid and gas fuels can be burned in the cyclone furnace construction illustrated, the constructions illustrated and hereinafter described are specifically designed and particularly adapted for burning coarsely pulverized or "granulated" bituminous or semibituminous coal.

70 The main portions of the unit illustrated in Figs. 1

and 2 include a fuel firing section consisting of a pair of cyclone furnaces 10 and 12 arranged to burn a solid fuel at high rates of heat release and discharging high temperature gaseous products of combustion and separated ash residue as a molten slag into a secondary furnace 14 formed in the lower portion of the fluid heating unit. The heating gases with some molten ash in suspension are directed upwardly within the secondary furnace 14, then flow through a slag collecting screen 16 into a vertically elongated radiant heat transfer chamber 18 of horizontal rectangular cross-section, and thence to a convection heating section, not shown.

The secondary furnace chamber 14 is of horizontal rectangular cross-section, being defined by a water-cooled rear or "target" wall 20, front wall 22 and opposite side walls 24, and partitioned from the cyclone furnaces 10, 12 by portions of the circumferential wall of each cyclone furnace chamber. The secondary furnace chamber 14 opens upwardly into the radiant chamber 18, which is formed by vertical extensions of the front, rear and side boundaries of the chamber 14. The lower end of the secondary furnace chamber includes inclined floor portions 26 converging downwardly toward a rectangular throat passage 28 for discharging molten slag into a slag tank, only a portion of which is shown, positioned therebelow.

The cyclone furnaces 10 and 12 are of horizontally elongated substantially circular cross-section, the furnace chamber of each being formed by closely spaced studded tubes covered by a layer of suitable refractory material and having its entire axial length disposed within the secondary furnace 14. Each furnace chamber includes a circumferential wall 30, a portion of which is also common to the front wall boundary of the secondary furnace chamber 14, and an end wall 32, which is also common to the plane of its corresponding secondary furnace chamber side wall boundary. The cyclone furnaces 10 and 12 are combined in end-to-end relation, to form a single furnace unit 34 having a lower outlet 36 opening tangentially toward one side thereof, adjacent the bottom, for the combined discharge of all gases and slag into the secondary furnace 14. The cyclone furnace chambers are formed about longitudinal axes inclined downwardly toward the center of the secondary furnace 14 in a common vertical plane so that the rotating fuel and air streams traveling along the circumferential wall of each furnace chamber, from axially opposite directions, will not leave a dead space in an upper part of the chamber. A whirling stream of primary air and fuel is introduced into each of the cyclone furnaces 10, 12 through a primary burner or head 38 which opens axially thereof through the walls 24 and 32, the two streams whirling in opposite directions, as viewed from the respective ends, but providing a common direction of rotation within the furnace unit 34 as viewed from a single end. Thus, as seen in Fig. 1, with the common outlet 36 positioned as shown, the direction of fuel-air rotation is counterclockwise. Secondary air is introduced tangentially into the furnace unit 34 in the same direction of rotation as the streams of fuel laden air through two sets of ports 40 located adjacent opposite ends.

All boundaries of the secondary furnace and radiant chambers 14 and 18 are fluid cooled by means of fluid conducting tubes associated with the respective walls. The rear wall 20 is lined by tubes 42 having their lower ends connected to a header 44. The circumferential wall of each furnace chamber includes oppositely curved rows of fluid cooled tubes 46 and 48, the former extending between lower headers 50 and upper headers 52 and the latter having their upper portions extending upwardly along the front wall 22 and their lower ends connected to headers 54. The slag screen 16 arranged across the outlet from the secondary furnace chamber 14 is formed by tubes 56 connected at opposite ends to headers 58 and 60 and having intermediate portions extending along

a portion of the circumferential wall of the corresponding furnace chamber. It is to be understood that the portions of the fluid circulation system described are suitably connected into the circulation system of the unit. For example, the upper ends of tube rows 42 and 48 may be connected to a steam and water drum and the headers 44 and 54 may be supplied with water from the water space of said drum. The rear wall 20, being an outer wall, and thus freely accessible from the outside, may be provided with a closable port, opposite the gas and slag outlet 36, and thereby enable inspection to be made of furnace operating conditions.

In the operation of the cyclone furnace 10, 12, the slag which is deposited on the walls is continuously contacted by the whirling stream of burning fuel and gases and thereby brushed through the common outlet 36 into the slag discharge opening 28 of the secondary furnace chamber 14. The gases discharging through the outlet 36 contain little, if any, combustible matter, combustion being substantially completed in the furnace unit 34. Fly ash and molten particles present in suspension in the outgoing gases are largely removed in the secondary furnace chamber 14. The rear or "target" wall 20 is positioned opposite the outlet 36 at a distance therefrom short enough to insure that the gases and suspended ash and molten particles will impact on the "target" wall at a velocity sufficient to cause most of the suspended ash and slag particles in a molten or sticky condition to adhere to the "target" wall, while large enough that the discharging gases will not flow upwardly through the lower portion of the secondary furnace chamber 14 at a velocity which would cause the slag deposited on the "target" wall to be picked up by the gases and carried into the convection heating section of the unit. In general a distance between the outlet 36 and the "target" wall 20 of not greater than one cyclone furnace diameter has been found to be satisfactory. With the "target" wall so arranged, the products of combustion from the furnace unit 34 discharge into the lower portion of the secondary furnace chamber 14 and due to the proximity of the wall 20 the gas stream impacts thereon and is forced to move upwardly. The adhesive property of the slag particles and this relatively abrupt change in direction of movement of the gas stream results in most of the remaining ash and slag particles in suspension being deposited on the wall 20 and from there drained downwardly to the slag tank. The gases then flow upwardly through the slag screen 16 into the radiant chamber 18, and thence to the convection heating section of the unit.

Fig. 3 is a modification diagrammatically illustrating an arrangement of two cyclone furnaces 62, 64 in which the increasing radial dimension from opposite ends facilitates the passage of slag into an outlet 66. In other respects, this form of furnace may be constructed in the manner of the furnace unit 34 and may be substituted therefor in the furnace arrangement shown in Figs. 1 and 2.

While in accordance with the provisions of the statutes I have illustrated and described herein a specific form of the invention now known to me, those skilled in the art will understand that changes may be made in the form of the apparatus disclosed without departing from the spirit of the invention covered by my claims, and that certain features of the invention may sometimes be used to advantage without a corresponding use of other features.

What is claimed is:

1. A fluid heating unit having a fluid circulation system and comprising upwardly extending walls including fluid cooled tubes defining a secondary furnace chamber, a cyclone furnace having a furnace chamber of substantially circular cross-section extending into said secondary furnace chamber and defined in part by a circumferential wall including intermediate portions of some of the fluid

cooled tubes of said secondary furnace chamber walls, means forming a gas outlet at one end of said furnace chamber opening to said secondary furnace chamber, means for introducing a combustible mixture into said furnace chamber for discharge through said gas outlet into said secondary furnace chamber, some of the fluid cooled tubes of said circumferential wall absorbing heat from the hot gases therein and from the gases flowing through said secondary furnace chamber, and means connecting said fluid cooled tubes into said fluid circulation system.

2. A fluid heating unit having a fluid circulation system and comprising upwardly extending walls including fluid cooled tubes defining a secondary furnace chamber, a cyclone furnace having a furnace chamber of substantially circular cross-section extending into said secondary furnace chamber and arranged with its major axis substantially horizontal, said furnace chamber being defined in part by a circumferential wall including intermediate portions of some of the fluid cooled tubes of said secondary furnace chamber walls, means forming a gas outlet at one end of said furnace chamber opening to said secondary furnace chamber, means for introducing a combustible mixture into said furnace chamber for discharge through said gas outlet into said secondary furnace chamber, some of the fluid cooled tubes of said circumferential wall absorbing heat from the hot gases therein and from the gases flowing through said secondary furnace chamber, and means connecting said fluid cooled tubes into said fluid circulation system.

3. A fluid heating unit having a fluid circulation system and comprising upwardly extending walls including fluid cooled tubes defining a secondary furnace chamber, a cyclone furnace having a furnace chamber of substantially circular cross-section arranged with its major axis substantially horizontal and defined by walls including intermediate portions of some of the fluid cooled tubes of said secondary furnace chamber walls, said furnace chamber having its entire axial length disposed in said secondary furnace chamber, means forming a gas outlet at one end of said furnace chamber opening to said secondary furnace chamber, means for introducing a combustible mixture into said furnace chamber for discharge through said gas outlet into said secondary furnace chamber, some of the fluid cooled tubes of said furnace chamber absorbing heat from the hot gases therein and from the gases flowing through said secondary furnace chamber, and means connecting said fluid cooled tubes into said fluid circulation system.

4. A fluid heating unit having a fluid circulation system and comprising upwardly extending walls including fluid cooled tubes defining a secondary furnace chamber, a cyclone furnace having a furnace chamber of substantially circular cross-section arranged with its major axis substantially horizontal and defined by walls including intermediate portions of some of the fluid cooled tubes of said secondary furnace chamber walls, said furnace chamber having its entire axial length disposed in said secondary furnace chamber, means forming a gas outlet at one end of said furnace chamber opening to said secondary furnace chamber, part of the fluid cooled circumferential wall of said furnace chamber being common with a wall of said secondary furnace chamber, means for introducing a combustible mixture into said furnace chamber for discharge through said gas outlet into said secondary furnace chamber, some of the fluid cooled tubes of said furnace chamber absorbing heat from the hot gases therein and from the gases flowing through said secondary furnace chamber, and means connecting said fluid cooled tubes into said fluid circulation system.

5. A fluid heating unit having a fluid circulation system and comprising upwardly extending walls including fluid cooled tubes defining a secondary furnace chamber, a cyclone furnace having a furnace chamber of substantially circular cross-section extending into said secondary fur-

nace chamber and defined by walls including intermediate portions of some of the fluid cooled tubes of said secondary furnace chamber walls, means for burning a slag-forming solid fuel in said furnace chamber under a mean furnace chamber temperature above the fuel ash fusion temperature, means forming an outlet at one end of said furnace chamber extending through and arranged tangentially to the circumferential wall of said furnace chamber for the discharge of molten slag and heating gases carrying slag particles in suspension into said secondary furnace chamber, some of the fluid cooled tubes of said furnace chamber absorbing heat from the hot gases therein and from the gases flowing through said secondary furnace chamber, and means connecting said fluid cooled tubes into said fluid circulation system.

6. A fluid heating unit having a fluid circulation system and comprising upwardly extending walls including fluid cooled tubes defining a secondary furnace chamber, a cyclone furnace having a furnace chamber of substantially circular cross-section extending into said secondary furnace chamber and arranged with its major axis substantially horizontal, said furnace chamber being defined by walls including intermediate portions of some of the fluid cooled tubes of said secondary furnace chamber walls, means for burning a slag-forming solid fuel in said furnace chamber under a mean furnace chamber temperature above the fuel ash fusion temperature, means forming an outlet at one end of said furnace chamber extending through and arranged tangentially to the circumferential wall of said furnace chamber for the discharge of molten slag and heating gases carrying slag particles in suspension into said secondary furnace chamber, some of the fluid cooled tubes of said furnace chamber absorbing heat from the hot gases therein and from the gases flowing through said secondary furnace chamber, and means connecting said fluid cooled tubes into said fluid circulation system.

7. A fluid heating unit having a fluid circulation system and comprising upwardly extending walls including fluid cooled tubes defining a secondary furnace chamber, a cyclone furnace having a furnace chamber of substantially circular cross-section arranged with its major axis substantially horizontal and defined by walls including intermediate portions of some of the fluid cooled tubes of said secondary furnace chamber walls, said furnace chamber having its entire axial length disposed in said secondary furnace chamber, means for burning a slag-forming solid fuel in said furnace chamber under a mean furnace chamber temperature above the fuel ash fusion temperature, means forming an outlet at one end of said furnace chamber extending through and arranged tangentially to the circumferential wall of said furnace chamber for the discharge of molten slag and heating gases carrying slag particles in suspension into said secondary furnace chamber, some of the fluid cooled tubes of said furnace chamber absorbing heat from the hot gases therein and from the gases flowing through said secondary furnace chamber, and means connecting said fluid cooled tubes into said fluid circulation system.

8. A fluid heating unit having a fluid circulation system and comprising upwardly extending walls including fluid cooled tubes defining a secondary furnace chamber, a cyclone furnace having a furnace chamber of substantially circular cross-section extending into said secondary furnace chamber and arranged with its major axis substantially horizontal, said furnace chamber being defined by walls including fluid cooled tubes, means for burning a slag-forming solid fuel in said furnace chamber under a mean furnace chamber temperature above the fuel ash fusion temperature, means forming an outlet at one end of said furnace chamber for the discharge of molten slag and heating gases carrying slag particles in suspension into said secondary furnace chamber, said secondary furnace chamber including a lower section having a vertically arranged outer wall opposite said gas and slag outlet

and spaced horizontally therefrom a distance not greater than the diameter of said cyclone furnace to receive the impact of a major portion of the slag particles in suspension in the discharged heating gases, some of the fluid cooled tubes of said furnace chamber absorbing heat from the hot gases therein and from the gases flowing through said secondary furnace chamber, and means connecting said fluid cooled tubes into said fluid circulation system.

9. A fluid heating unit having a fluid circulation system and comprising upwardly extending walls including fluid cooled tubes defining a secondary furnace chamber, a cyclone furnace having a furnace chamber of substantially circular cross-section extending into said secondary furnace chamber and arranged with its major axis substantially horizontal, said furnace chamber being defined by walls including intermediate portions of some of the fluid cooled tubes of said secondary furnace chamber walls, means for burning a slag-forming solid fuel in said furnace chamber under a mean furnace chamber temperature above the fuel ash fusion temperature, means forming an outlet at one end of said furnace chamber extending through and arranged tangentially to the circumferential wall of said furnace chamber for the discharge of molten slag and heating gases carrying slag particles in suspension into said secondary furnace chamber, said secondary furnace chamber including a lower section having a vertically arranged outer wall opposite said gas and slag outlet and spaced horizontally therefrom a distance not greater than the diameter of said cyclone furnace to receive the impact of a major portion of the slag particles in suspension in the discharged heating gases, some of the fluid cooled tubes of said furnace chamber absorbing heat from the hot gases therein and from the gases flowing through said secondary furnace chamber, and means connecting said fluid cooled tubes into said fluid circulation system.

10. A fluid heating unit having a fluid circulation system and comprising upwardly extending walls including fluid cooled tubes defining a secondary furnace chamber, a cyclone furnace having a furnace chamber of substantially circular cross-section arranged with its major axis substantially horizontal and defined by walls including intermediate portions of some of the fluid cooled tubes of said secondary furnace chamber walls, said furnace chamber having its entire axial length disposed in said secondary furnace chamber, means for burning a slag-forming solid fuel in said furnace chamber under a mean furnace chamber temperature above the fuel ash fusion temperature, means forming an outlet at one end of said furnace chamber extending through and arranged tangentially to the circumferential wall of said furnace chamber for the discharge of molten slag and heating gases carrying slag particles in suspension into said secondary furnace chamber, said secondary furnace chamber including a lower section having a vertically arranged outer wall opposite said gas and slag outlet and spaced horizontally therefrom a distance not greater than the diameter of said cyclone furnace to receive the impact of a major portion of the slag particles in suspension in the discharged heating gases, some of the fluid cooled tubes of said furnace chamber absorbing heat from the hot gases therein and from the gases flowing through said secondary furnace chamber, and means connecting said fluid cooled tubes into said fluid circulation system.

11. A fluid heating unit having a fluid circulation system and comprising upwardly extending walls including fluid cooled tubes defining a secondary furnace chamber, a pair of cyclone furnaces each having a furnace chamber of substantially circular cross-section extending into said secondary furnace chamber and defined by walls including intermediate portions of some of the fluid cooled tubes of said secondary furnace chamber walls, said cyclone furnaces being arranged in separate walls of said secondary furnace chamber and having their furnace

chambers in communicating relationship, means forming a gas outlet common to said furnace chambers opening to said secondary furnace chamber, means for introducing a combustible mixture into each furnace chamber for discharge through said gas outlet into said secondary furnace chamber, some of the fluid cooled tubes of each furnace chamber absorbing heat concurrently from the hot gases therein and from the gases flowing through said secondary furnace chamber, and means connecting said fluid cooled tubes into said fluid circulation system.

12. A fluid heating unit having a fluid circulation system and comprising upwardly extending walls including fluid cooled tubes defining a secondary furnace chamber, a pair of cyclone furnaces each having a furnace chamber of substantially circular cross-section extending into said secondary furnace chamber and arranged with its major axis substantially horizontal, each of said furnace chambers being defined by walls including intermediate portions of some of the fluid cooled tubes of said secondary furnace chamber walls, said cyclone furnaces being arranged in separate walls of said secondary furnace chamber and having their furnace chambers in communicating relationship, means forming a gas outlet common to said furnace chambers opening to said secondary furnace chamber, means for introducing a combustible mixture into each furnace chamber for discharge through said gas outlet into said secondary furnace chamber, some of the fluid cooled tubes of each furnace chamber absorbing heat concurrently from the hot gases therein and from the gases flowing through said secondary furnace chamber, and means connecting said fluid cooled tubes into said fluid circulation system.

13. A fluid heating unit having a fluid circulation system and comprising upwardly extending walls including fluid cooled tubes defining a secondary furnace chamber, a pair of cyclone furnaces each having a furnace chamber of substantially circular cross-section arranged with its major axis substantially horizontal and defined by walls including intermediate portions of some of the fluid cooled tubes of said secondary furnace chamber walls, each of said furnace chambers having its entire axial length extending into said secondary furnace chamber, said cyclone furnaces being arranged in separate walls of said secondary furnace chamber and having their furnace chambers in communicating relationship, means forming a gas outlet common to said furnace chambers opening to said secondary furnace chamber, means for introducing a combustible mixture into each furnace chamber for discharge through said gas outlet into said secondary furnace chamber, some of the fluid cooled tubes of each furnace chamber absorbing heat concurrently from the hot gases therein and from the gases flowing through said secondary furnace chamber, and means connecting said fluid cooled tubes into said fluid circulation system.

14. A fluid heating unit having a fluid circulation system and comprising upwardly extending walls including fluid cooled tubes defining a secondary furnace chamber, a pair of cyclone furnaces each having a furnace chamber of substantially circular cross-section extending into said secondary furnace chamber and arranged with its major axis substantially horizontal, each of said furnace chambers being defined by walls including intermediate portions of some of the fluid cooled tubes of said secondary furnace chamber walls, said cyclone furnaces being arranged in opposite walls of said secondary furnace chamber and having their furnace chambers in coaxial and communicating relationship, means forming a gas opening to said secondary furnace chambers, means for introducing a combustible mixture into each furnace chamber for discharge through said gas outlet into said secondary furnace chamber, some of the fluid cooled tubes of each furnace chamber absorbing heat concurrently from the hot gases therein and from the gases flowing through said secondary furnace chamber, and

means connecting said fluid cooled tubes into said fluid circulation system.

15. A fluid heating unit having a fluid circulation system and comprising upwardly extending walls including fluid cooled tubes defining a secondary furnace chamber, a pair of cyclone furnaces each having a furnace chamber of substantially circular cross-section extending into said secondary furnace chamber and defined by walls including intermediate portions of some of the fluid cooled tubes of said secondary furnace chamber walls, said cyclone furnaces being arranged in separate walls of said secondary furnace chamber and having their furnace chambers in communicating relationship, means for burning a slag-forming solid fuel in each of said furnace chambers under a mean furnace chamber temperature above the fuel ash fusion temperature, means forming a gas outlet common to said furnace chambers opening to said secondary furnace chamber, some of the fluid cooled tubes of each furnace chamber absorbing heat concurrently from the hot gases therein and from the gases flowing through said secondary furnace chamber, and means connecting said fluid cooled tubes into said fluid circulation system.

16. A fluid heating unit having a fluid circulation system and comprising upwardly extending walls including fluid cooled tubes defining a secondary furnace chamber, a pair of cyclone furnaces each having a furnace chamber of substantially circular cross-section extending into said secondary furnace chamber and arranged with its major axis substantially horizontal, each of said furnace chambers being defined by walls including intermediate portions of some of the fluid cooled tubes of said secondary furnace chamber walls, said cyclone furnaces being arranged in separate walls of said secondary furnace chamber and having their furnace chambers in communicating relationship, means for burning a slag-forming solid fuel in each of said furnace chambers under a mean furnace chamber temperature above the fuel ash fusion temperature, means forming a gas outlet common to said furnace chambers opening to said secondary furnace chamber, some of the fluid cooled tubes of each furnace chamber absorbing heat concurrently from the hot gases therein and from the gases flowing through said secondary furnace chamber, and means connecting said fluid cooled tubes into said fluid circulation system.

17. A fluid heating unit having a fluid circulation system and comprising upwardly extending walls including fluid cooled tubes defining a secondary furnace chamber, a pair of cyclone furnaces each having a furnace chamber of substantially circular cross-section extending into said secondary furnace chamber and arranged with its major axis substantially horizontal, each of said furnace chambers being defined by walls including intermediate portions of some of the fluid cooled tubes of said secondary furnace chamber walls, said cyclone furnaces being arranged in opposite walls of said secondary furnace chamber and having their furnace chambers in coaxial and communicating relationship, means for burning a slag-forming solid fuel in each of said furnace chambers under a mean furnace chamber temperature above the fuel ash fusion temperature, means forming an outlet common to said furnace chambers extending through and arranged tangentially to the circumferential walls of said furnace chambers for the discharge of molten slag and heating gases carrying slag particles in suspension into said secondary furnace chamber, some of the fluid cooled tubes of each furnace chamber absorbing heat concurrently from the hot gases therein and from the gases flowing through said secondary furnace chamber, and means connecting said fluid cooled tubes into said fluid circulation system.

18. A fluid heating unit having a fluid circulation system and comprising upwardly extending walls including fluid cooled tubes defining a secondary furnace chamber, a pair of cyclone furnaces each having a furnace cham-

ber of substantially circular cross-section extending into said secondary furnace chamber and arranged with its major axis substantially horizontal, each of said furnace chambers being defined by walls including fluid cooled tubes, said cyclone furnaces being arranged in separate walls of said secondary furnace chamber and having their furnace chambers in communicating relationship, means for burning a slag-forming solid fuel in each of said furnace chambers under a mean furnace chamber temperature above the fuel ash fusion temperature, means forming an outlet common to said furnace chambers for the discharge of molten slag and heating gases carrying slag particles in suspension into said secondary furnace chamber, said secondary furnace chamber including a lower section having a vertically arranged outer wall opposite said gas and slag outlet and spaced horizontally therefrom a distance not greater than the diameter of said cyclone furnace to receive the impact of a major portion of the slag particles in suspension in the discharged heating gases, some of the fluid cooled tubes of each furnace chamber absorbing heat concurrently from the hot gases therein and from the gases flowing through said secondary furnace chamber, and means connecting said fluid cooled tubes into said fluid circulation system.

25. 19. A fluid heating unit having a fluid circulation system and comprising upwardly extending walls including fluid cooled tubes defining a secondary furnace chamber, a pair of cyclone furnaces each having a furnace chamber of substantially circular cross-section extending into said secondary furnace chamber and arranged with its major axis substantially horizontal, each of said furnace chambers being defined by walls including intermediate portions of some of the fluid cooled tubes of said secondary furnace chamber walls, said cyclone furnaces being arranged in separate walls of said secondary furnace chamber and having their furnace chambers in communicating relationship, means for burning a slag-forming solid fuel in each of said furnace chambers under a mean furnace chamber temperature above the fuel ash fusion temperature, means forming an outlet common to said furnace chambers for the discharge of molten slag and heating gases carrying slag particles in suspension into said secondary furnace chamber, said secondary furnace chamber including a lower section having a vertically arranged outer wall opposite said gas and slag outlet and spaced horizontally therefrom a distance not greater than the diameter of said cyclone furnace to receive the impact of a major portion of the slag particles in suspension in the discharged heating gases, some of the fluid cooled tubes of each furnace chamber absorbing heat concurrently from the hot gases therein and from the gases flowing through said secondary furnace chamber, and means connecting said fluid cooled tubes into said fluid circulation system.

40. 20. A fluid heating unit having a fluid circulation system and comprising upwardly extending walls including fluid cooled tubes defining a secondary furnace chamber, a pair of cyclone furnaces each having a furnace chamber of substantially circular cross-section arranged with its major axis substantially horizontal and defined by walls including intermediate portions of some of the fluid cooled tubes of said secondary furnace chamber walls, said cyclone furnaces being arranged in opposite walls of said secondary furnace chamber and having their furnace chambers in coaxial and communicating relationship, means for burning a slag-forming solid fuel in each of said furnace chambers under a mean furnace chamber temperature above the fuel ash fusion temperature, means forming an outlet common to said furnace chambers extending through and arranged tangentially to the circumferential walls of said furnace chambers for the discharge of molten slag and heating gases carrying slag particles in suspension into said secondary furnace chamber, said secondary furnace chamber including a lower section having a vertically arranged outer wall opposite said gas and slag outlet and spaced horizontally therefrom a distance not

greater than the diameter of said cyclone furnace to receive the impact of a major portion of the slag particles in suspension in the discharged heating gases, some of the fluid cooled tubes of each furnace chamber absorbing heat concurrently from the hot gases therein and from the 5 gases flowing through said secondary furnace chamber, and means connecting said fluid cooled tubes into said fluid circulation system.
